GRASS SHEARS WITH PUSH ROD ROLLERS

Carl H. William Kahl, Phoenix, Ariz.

Application January 9, 1953, Serial No. 330,496

2 Claims. (Cl. 56—241)

1

This invention relates to grass shears operated with a minimum of friction, equipped with a shock absorber, and improved by a body weight appliance.

Hand-operated shears are still in use, but fingers get cramped, blisters develop, and the work progresses slowly. Larger shears, for two-handed operation, with arms extended, wear a man out. Other apparatus with mechanical transmission are being operated from a standing posture, but they are either handicapped by excess friction or a blunt mechanism that taxes the strength of the operator.

In view of the foregoing, the first object of my device is to enable a man to use these grass shears without having to kneel down.

Another object is to eliminate the use of hand pressure, and, instead, to bring one's arms and body weight into play for pushing the shears shut.

Another object is to provide shears with longer and more powerful blades than those operated by single hand pressure and still retain a smoothly working apparatus that will not tire the operator.

Still another object is to equip this cutting device with a plunger which requires but a short stroke, so that the operator may get results by short, swift jabs upon the plunger, with arm motion and little back bending.

Another objective is to create a device which is simple in construction, easily fabricated and at no great cost.

Still another object is to all but eliminate friction within the mechanical transmission of the power obtained through the plunger.

Another object is to eliminate the shock which is incurred in certain devices which are designed to ram a push rod against a solid metal unit, such as a lever or a bell crank. Instead, my object is to construct a smoothly rolling propulsion device which exerts cumulative pressure upon the shear arms.

Another object is to eliminate a second shock, harmful to the whole mechanism. This shock is incurred when the propulsion device is permitted to slam the shear arms together or against a post. My object is to install a buffer, a shock absorber, in order to hold wear and tear of the component parts down to a minimum.

I attain the foregoing objectives by means of the devices and construction illustrated in the accompanying drawings, in which

Figure 1 is a perspective view of the assembled apparatus, standing upright upon its metal base.

2

Figure 2 is a side elevation of the lower part of the device, affording a view of the shears connected to the metal base and to the propelling rods.

Figure 3 is a back elevation of the device, without the guard and the toe strap.

Similar numbers refer to similar parts in the several views.

Referring to the drawings, Figure 1 shows the complete assembly of the apparatus, which includes a pair of metal shears 1, mounted on a metal base 2, with sides 20 bent down at right angles. The sides 20 of said metal base taper up to the front to permit a tilting of the shear blades. The king bolt 3 of the shears is replaced by a longer bolt 3 to penetrate both the shears and the base plate, with a nut 4 below. A spring 5 holds the shear arms 21 apart.

An operating mast 6 (pipe) leaning slightly backwards, is fastened in a socket 7 which is riveted or welded upon the base plate. Halfway up the mast, two rods 8, hinged by loose bolt connection 22, reach downward for insertion into holes 9, drilled in the ends of the shear arms. These rods 8 are the propelling rods.

A plunger 10 is attached to a carriage 11, with two grooved wheels 12, which are designed to roll partway down the said propelling rods and cause the shears to close. The opening 9 in the shear arms must permit a sliding motion of the rod ends, because, when being pressed together, the rod ends describe an arc downward, while the shear arms move on a horizontal plane.

A guide slot 13, across the base plate, is provided to steady the movement of the shear arms.

The plunger 10 extends downward below the carriage 11 to form a buffer 14 which will strike the base plate at the end of the downward stroke, thus taking the shock off the rods and the shear arms. The plunger is equipped with a guide bracket 15, steadyng it by sliding up and down the mast.

Two light springs 16 connect the top of the mast with the carriage 11 for the pull back up.

A stop collar 17, near the top of the mast, checks the upward stroke.

An upright metal guard 18, behind the mast, prevents the operator's toe from getting under the buffer.

A toe strap 19 is added for pushing the device about.

The construction of this apparatus is very simple, and its function can be grasped at a glance. The manipulation of the cutters is so easy and

the leverage so powerful that long blades may be used.

When the assembly is made as above stated, the operation of the shears is accomplished by short downward jabs upon the plunger. There is no jarring start and no jerky mechanism. The carriage with its two grooved wheels gets underway smoothly, in a gliding motion, with cumulative force and little friction. And since the propelling rods are hooked up to the shear arms, the latter move simultaneously, and the shears snap shut.

There is no deep plunge involved, and therefore little back bending; for the shears close when the grooved wheels have tracked only halfway down the propelling rods.

The closing of the shears is timed by the length of the buffer. This shock absorber is merely an extension of the plunger, below the carriage, and is designed to hit the base plate at just the right time to close the shears fully and yet prevent the shear arms from hitting together. In this manner the shock upon the mechanism is diverted from both the propelling rods and the shears, and is absorbed by the more robust plunger. Also a good deal of friction is eliminated by the installation of this buffer, and the operator may push the plunger as vigorously as he desires.

The plunger and carriage are pulled back up by the springs from the mast top. The stop collar, near the top of the mast, halts the plunger on its way up.

Due to the short travel of the plunger, the opening and the shutting of the blades can be repeated rapidly and without great effort.

For cutting grass or weeds closer to the ground, the apparatus may be tilted forward. The tilting is facilitated by two factors: the sides of the base plate tapering forward, and a lift on the toe strap to support the tilt.

A powerful leverage is exerted upon the shear arms as the plunger forces the grooved wheels down the propelling rods; and the cutting of grass and weeds is accomplished by a decisive force; yet, due to the wheeling motion and the cumulative pressure obtained in this device, no great muscular effort is required to operate it.

I claim:

1. Grass shears comprising a ground-contacting base plate; shears mounted upon said plate by a kingbolt; an upright mast situated between the shear arms and secured at its lower end to the said base plate, two round metal propelling rods hinged by loose bolt connection halfway up the said mast and extending down angularly and outwardly, their lower ends fitting into holes drilled into the ends of the said shear arms; a

metal guide bracket fastened to the said base plate to cover the path and to steady the movement of the said shear arms; a double-rod plunger with a two-fist grip handle and a guide bracket slideably mounted on the said mast, one of the said plunger rods being positioned on either side of said mast; two small pulley wheels laterally disposed on axles within a rectangular metal frame attached to the said plunger rods; the said mast being positioned inside the said rectangular frame, one of the said pulley wheels being positioned on either side of said mast, each one of said pulley wheels being provided with a rim groove fitting snugly upon the outer face of one of the said propelling rods, the said wheels being spaced close together within the said rectangular frame and so arranged that downward motion of the said plunger will cause the said wheels to track down on the said diverging rods, closing in on them, forcing the lower ends of the said rods together towards the said mast and causing the said shear arms to close.

2. In a grass shears, a vertically disposed mast rigidly secured upon a metal base plate; shears mounted at the front end of the said base plate, one shear arm being positioned on either side of said mast; a plunger attached to a guide bracket slideable upon the said mast; an extension at the bottom of the said plunger, forming a buffer stop and serving as a shock absorber of the shearing device, the impact of the said plunger extension against the said base plate being synchronized with the closing of the said shear arms, averting a clanking together of the said shear arms or a slamming of the said shear arms against the said mast, said buffer taking the jar off the more delicate mechanism of this device, reducing wear and tear; an upright metal shield fastened upon the said base plate, right behind the point of contact with the said buffer, preventing the operator's toe from getting under the said buffer; a leather shoe strap doming the rear of the said base plate and fastened thereto; a stout steel spring between the said shear arms, forcing the shears to reopen; a stop collar set at a point on the said mast to limit the return move of the said plunger; and two springs from the top of the said mast to the said guide bracket of the said plunger, to ease the return move of the said plunger.
